UNITED STATES PATENT OFFICE.

CHARLES H. SCHOPBACH, OF AURORA, ILLINOIS, ASSIGNOR TO INTERNATIONAL CORSET COMPANY, OF AURORA, ILLINOIS, A CORPORATION OF ILLINOIS.

CORSET.

1,347,180.

Specification of Letters Patent.

Patented July 20, 1920.

Application filed November 7, 1918. Serial No. 261,579.

To all whom it may concern:

Be it known that I, CHARLES H. SCHOPBACH, a citizen of the United States, and a resident of Aurora, in the county of Kane and State of Illinois, have invented certain new and useful Improvements in Corsets; and I do hereby declare that the following is a full, clear, and exact description thereof, reference being had to the accompanying 10 drawings, and to the letters of reference marked thereon, which form a part of this specification.

This invention relates to improvements in front lace corsets and more particularly in 15 that type of front lace corsets wherein the lower portion of the fabric is extended below the lower ends of the eyelet and clasp stays.

Heretofore in this type of corsets, it has 20 been desirable to use hose supporters attached to the front of the corset at the lower end of the fabric that supports the end of the eyelet stays, and also to use other hose supporters attached to the fabric that extends 25 below the ends of the corset stays. Thus a plurality of hose supporters for each side of the corset have been used, and the convenience of these supporters has been such that corsets with three and four of such 30 supporters on each side of the corset have become so popular as to make it almost imperative from the manufacturer's standpoint, to use that number of supporters.

In the present emergency, the Government 35 has been obliged to make certain restrictions governing the manufacture of corsets. Among these, the Government has laid down the rule that but two hose supporters be used for each side of the corset.

Naturally, where but two such supporters 40 are used, they are spaced at some considerable distance apart, so that the portion of the supporter intended to engage the hose will do so at substantially diametrically opposite parts of the top of the hose, to thus hold it more properly upon the limb of the wearer.

The securing of one hose supporter to 45 the garment at the lower end of the eyelet stays, and of the other hose supporter at a considerable remove therefrom, provides nothing in the intervening space to hold down the lower part of the fabric between the two supporters. Such fabric, in use, 50 becomes folded and wrinkled and very ob-

jectionable to the wearer. This part of the fabric must be thin and very flexible, and is not provided with stays to its lower margin in order to afford freedom to the user of the corset when stooping over or in a sitting posture. Hence, while having flexibility and freedom, provision must also be made for holding it in its relative position and in its smooth or straightened out arrangement. This has heretofore been accomplished by having a garment supporter attached where needed. Such third supporter I now propose to remove, under Government direction, as stated, heretofore.

The principal object of my invention, 70 therefore, is to provide a device which will accomplish that part of the function of the garment supporter intended to hold the fabric intervening between the two remaining supporters, in its normal position, free 75 from wrinkles and yet hold it with the requisite degree of freedom and flexibility.

In the drawing:

Figure 1 shows a front lace corset of the usual type, to which my invention has been 80 applied.

Fig. 2 is an enlarged, sectional view of a portion of the corset, taken upon the horizontal plane indicated by the dotted line 2-2 of Fig. 1.

In said drawing, A indicates the corset as a whole, comprising a right hand body member 1 and a left hand body member 2. Attached to the longitudinal front margin of the body member 2 is an eyelet stay member 3. A similar eyelet stay member 4 is provided, whereby the usual strings or corset lacings may be passed between the two eyelet members 3 and 4 in a familiar manner. The margin of the member 1 is 90 provided, also, with a longitudinally arranged stay member 6 and corset clasps are provided, one member 7 being attached to the stay 6 and the other member 8 being attached to the eyelet stay 4, whereby the corset body 2 and the corset body 1 may be hooked together by the wearer in a familiar manner.

In this type of corset, the stay members 3 and 4 are of such length that their lower 105 ends 9, 9 extend down as far as possible on the body when the corset is upon the wearer and yet provide freedom of movement when the wearer bends over or assumes a sitting posture. The cloth, or fabric, however, in 110

this type of corsets, as shown, extends considerably below the ends 9, 9, and to the lower margin 10, 10, of the fabric, I attach the upper end of an elastic hose supporter 11, 11,—one on each side. To the lower ends 9, 9, I also attach the upper end of a hose supporter, 12, 12. These hose supporters serve to unite the clasp with the hose and to hold the hose up as well as to hold 10 the corset down.

The portion of the fabric of the body 1 and the body 2, indicated generally below the dotted line 13 and designated by the numeral 14, provides a triangularly shaped 15 strip with a substantially horizontal margin 15 and a substantially vertical margin 16. It is this portion 14 that it is required to be yielding or flexible, and yet so constructed as not to wrinkle and fold. To this 20 end, I provide a piece of non-elastic fabric 17 which by folding between its ends and uniting the two free ends, forms a loop 18; the free ends 19 being secured by stitches 25 to the margin 16 of the corset fabric. Through this loop 18 I pass the hose supporter 12. The length of this loop 18 and its width, relatively to the width of the hose supporter 12, are such that when the corset 30 is in position and the hose supporter 12 fastened to the hose of the wearer, the front end 21 of the loop 18 will substantially bear along the side margin or edge of the elastic strip of the hose supporter 12. This loop 35 18 in practice will thus be found to perform two functions,—first: by being held by the location of the hose supporter 12 in a relatively fixed position, no practical, lateral movement will be possible of that portion of the corset fabric designated at 14; although there will be, by reason of the loop 40 construction, a small amount of play. This will prevent wrinkling or folding, so far as lateral or side-wise movement is concerned.

It will also be found that, by reason of the engagement of the end 21 of the loop 18 with the margin of the elastic portion of the hose supporter 12, and of the relative width of the non-elastic fabric comprising 50 the loop 18,—the frictional contact is such as to substantially hold the loop 18 in its lowermost position, thus holding the margin 15 of the fabric in proper position.

The strain on the hose supporter will be found such as to hold this loop in substantially taut engagement therewith, although yieldingly so. In other words, it is found in practice that this fabric portion 14, provided at its lower inner margin with the 55 loop 18, as shown, does not in fact slide or creep up on the wearer and does not wrinkle or crease. Thus, this simple expedient enables me to entirely dispense with

the intermediate hose supporter heretofore used, and indicated by the dotted lines 12^a, 65 the position of such dispensed-with supporter being so indicated in dotted lines on the left-hand side only in Fig. 1.

I claim as my invention:

1. In a front lace corset in which a portion of the fabric extends below the fastening and lacing stays, a hose supporter secured at its upper end to the lower end of a front stay and extending parallel with the free margin of said fabric, and means secured to said free margin coöperating with said supporter and loosely embracing the latter and preventing lateral wrinkling or folding of the fabric, substantially as and for the purpose specified. 70 80

2. In a front lace corset in which a portion of the fabric extends below the fastening and lacing stays, a hose supporter secured at its upper end to the lower end of a front stay and extending parallel with the free margin of said fabric, and means secured to said free margin coöperating with said supporter, said means comprising a loop of fabric having its free ends secured to the said free margin with the loop portion freely embracing the supporter and by frictional contact holding the margin of the fabric in proper position and preventing wrinkling. 85 90

3. In a front lace corset, two body portions, a lacing stay provided with eyelets and secured to the margin of one body portion, a clasp stay provided with a clasp member and secured to the margin of the other body portion, a second lace stay provided with eyelets and with a complementary clasp member, lacings to engage the two eyelet stays, the two body portions at either side of said stays extending below the line of the lower ends of said stays, a hose supporter secured to and extending below the lower end of the first mentioned eyelet stay, a second hose supporter secured to and extending below the lower end of the clasp stay and loop strap members secured to the 100 free margins of the body portion of the fabric adjacent to and having the loops in frictional engagement with said hose supporters, and by frictional contact therewith holding the margin of the fabric in proper 105 position and preventing wrinkling, substantially as and for the purpose specified. 110 115

In testimony that I claim the foregoing as my invention I affix my signature in the presence of three witnesses, this 5th day of November, A. D. 1918.

CHARLES H. SCHOPBACH.
